LEG MARKING DEVICE

Eugenie Marchado, New York, N. Y.

Application February 26, 1943, Serial No. 477,211

2 Claims. (Cl. 41—17)

This invention relates to leg marking devices.

The object of this invention is to provide a simple device which may be readily applied and removed after the markings have been made.

The invention consists of leg marking device having a spaced pair of hems enclosing a strip with transferable color thereon, with means of attaching it to the rear of the leg and, if desired, to the heel.

The invention will be further described, and embodiments thereof shown in the drawing, and then finally pointed out in the claims.

In the accompanying drawing—

Fig. 1 is a plan view of the improved device;

Fig. 2 is a section on line 2—2 of Fig. 1;

Fig. 3 is a side view;

Fig. 4 is a front view of a modified form;

Fig. 5 is a front view of another modification, and

Fig. 6 shows the manner of applying an embodiment of my invention.

Similar characters of reference indicate corresponding parts throughout the various views.

Referring to the drawing, and more particularly to Figures 1, 2 and 3, a strip 10 of cloth suitable to hold a dye of mordant colors or color mixture and impregnated therewith extends from end to end of the device.

At each lateral edge of this strip 10, hems 11 and 12 are sewed, stitched or otherwise attached to the strip 10 with the edges of the inwardly extending walls of the hems providing a narrow space between the inner edges 13 of the hems. The stitching is shown by 14. The length of the insert 10 and spaced hems 11 and 12 is about the length from the rear of the hems to the rear of the article. The longitudinal ends of the device are closed by stitching or the like as shown by 15, to prevent the unraveling of the textile materials used.

To each end, strips 16 and 17 are suitably attached in order to tie the improved device to the limb to be marked, and hold the device in position thereon while the marking takes place. Then a sharp instrument, such as a pencil, crayon or the like is pressed over the strip, and either the dye in the strip is transferred to the skin, or if the strip is not dyed, the crayon particles pass through the interstices of the strip and are transferred to the skin.

In Figures 4 and 5, the strip is widened at its lower part, as shown, to represent the conventional heel portions 20 and 21 of hosiery, and the dye of the insert is transferred to the heel portion of the limb to simulate the character-

istics of hosiery by pressure applied by means of a pencil, crayon, or the like. If the insert is not provided with a dye, a suitable crayon may be pressed on the insert and thereby the particles of the crayon pressed through the interstices of the insert. The hems extending along the edges of this widened portion act as guides for the pencil to indicate the outline of the widened space, which is then filled in by pressure applied to the widened insert over its entire surface, so as to transfer the color to the skin and form a similitude to the conventional heel portion of the hosiery.

No liquid paint is used, and by the device described, a clean transference takes place, and the device may be used many times over.

The insert is made preferably of some suitable textile material which will hold a transferable dye or the like, and which has been previously dye treated before being combined with the hems. The hems may be made of suitable textile fabric sufficiently stiff to provide at the inwardly extending edges a guideway for the pencil like tool to pass therebetween and to be guided thereby. Preferably, I have found the use of leather or leather imitation to be more durable and neater, and the use of the same provides relatively rigid edges for forming a guideway for the pencil like tool. The marking on the skin is clear and distinct and does not run, and while it may be washed off, is relatively permanent.

From the foregoing it is believed that the construction, operation and advantages of my invention may be readily understood by those skilled in the art without further description, it being borne in mind that numerous changes may be made in the details disclosed without departing from the spirit of the invention as set out in the following claims.

40 What I claim is:

1. A re-use device for marking legs, comprising a strip of cloth about the length of a leg and having interstices for transferable colors, layers superposed on said strip and extending substantially the length of the strip and laterally spaced from each other to enable their opposed parallel edges to form an uncovered elongated space exposing the cloth strip substantially the width of the configuration of the marking desired to be made on the leg, and fastening straps at each end of the cloth strip adapted to extend around the leg to be marked and hold the device in position thereon while the marking takes place by pressure applied to the exposed part of the cloth strip.

2. A re-use device for marking legs, comprising a strip of cloth about the length of a leg and having interstices for transferable colors, cloth layers superposed on said strip and extending substantially the length of the strip and laterally spaced from each other to enable their opposed parallel edges to form an uncovered elongated space exposing the cloth strip substantially the width of the configuration of the marking desired to be made on the leg, fastening straps at each end of the cloth strip adapted to

5 extend around the leg to be marked and hold the device in position thereon while the marking takes place by pressure applied to the exposed part of the cloth strip, and said layers having their edges spaced a greater distance apart than when forming the first exposed space, to form at one end of the devices an enlarged exposed space in similitude to the conventional heel inserts of hosiery.

10
